UNITED STATES PATENT OFFICE.

ARTHUR C. HOPKINS, OF NILES, MICHIGAN, ASSIGNOR TO NATIONAL STANDARD COMPANY, OF NILES, MICHIGAN.

BRAIDING MACHINE.

Application filed July 24, 1925, Serial No. 45,812. Renewed January 5, 1927.

This invention relates to improvements in braiding machines.

The main objects of this invention are:

First, to provide an improved braiding machine which is well adapted for braiding wire.

Second, to provide an improved braiding machine which is adapted to form braids which are substantially non-stretchable longitudinally and one in which the strands are under uniform stress.

Third, to provide an improved braiding machine which is well adapted to form cable-like strands comprising a plurality of wires uniformly interlocked throughout the length of the strand.

Fourth, to provide an improved braiding machine which is adapted for forming braids or cables at high speed.

Objects pertaining to details and economies of construction and operation of my invention will definitely appear from the detailed description to follow.

I accomplish the objects of my invention by the devices and means described in the following specification. The invention is clearly defined and pointed out in the claims.

A structure embodying the features of my invention is clearly illustrated in the accompanying drawing forming a part of this application, in which:

Fig. I is a fragmentary side elevation of a braiding machine embodying the features of my invention.

Fig. II is a fragmentary elevation partially in vertical section.

Fig. III is a fragmentary view mainly in vertical section on a line corresponding to line 3—3 of Fig. I.

Fig. IV is a fragmentary elevation of the capstan or take-off of the machine.

Fig. V is an enlarged detail section on a line corresponding to line 5—5 of Figs. I and VI showing structural details of the braider heads.

Fig. VI is a fragmentary plan view showing further details of the braiding heads.

Fig. VII is a fragmentary section on a line corresponding to line 7—7 of Figs. I, III, VIII and IX showing details of the forming and killing rolls.

Fig. VIII is a detail view partially in section on a line 8—8 of Fig. VII showing further details of the forming and killing rolls.

Fig. IX is a fragmentary front elevation 55 of the forming rolls.

Fig. X is a fragmentary plan view of a section of the fabric, the strands being shown in full black lines for convenience in illustration.

Fig. XI is a fragmentary section corresponding to that of Fig. VIII showing a modification in the forming and killing rolls.

Fig. XII is an enlarged detail section of the forming roll of the modification of Fig. XI.

Fig. XIII is a plan view of a section of the product of the machine equipped with the modified form of forming and killing rolls.

Fig. XIV is a conventionalized illustration of the article shown in Fig. XIII showing the general spiral character of the article.

In the drawing the sectional views are taken looking in the direction of the little arrows at the ends of the section lines and similar numerals of reference indicate similar parts throughout the several views.

Referring to the drawing, my improved braiding machine comprises the uprights 1 on which are mounted the segmental frame members 2 and 3. Extending across the upper end of the segmental frame members 3 is a bar 4 having formed as an integral part thereof, preferably as a casting, a segmental hanger 5 on which parts are mounted to be hereinafter described.

This segmental hanger is connected to the bar 4 by means of the tie-piece 6. The frame members 2 and 3 are provided with grooved rollers 7 constituting supports for the annular gears 8 by means of which the braider heads are driven, as will be hereinafter described. These annular gears 8 are both in mesh with a driving gear 9 on the shaft 10 which is connected by the transmission shaft 11 and the beveled gears 12 and 13 to the shaft 10 and the driving shaft 14, respectively. This shaft 14 has a pulley 15 thereon by means of which the machine is connected to a suitable source of power.

The braider heads each comprise complementary segmental sections 16 and 17 which are bolted upon the frame members 2 and 3 with their inner edges in spaced relation providing a throat 18 as shown in Figs. IV and V.

The frame members 2 and 3 are suitably spaced by the spacers 19, see Fig. V, which are extended to support the bearings 20 for the grooved rollers 7. These spacers are reduced at 21 and the purpose of this reducing will be pointed out later.

The head members 16 and 17 are provided with segmental tracks or ways consisting of the inner member 22 and the outer members 10 23 for the bobbin-carriers 24, there being a bobbin-carrier for each head member. These bobbin-carriers have flange-like segmental parts 25 engaging the tracks or ways.

Each bobbin-carrier has an upwardly projecting arm 26 provided with a bobbin spindle 27 for the bobbins 28. The carriers have segmental gears 29 adapted to coact with the annular gears 8. The gears 29 are of such length that before they are released by one 20 of the gears 8, they are engaged by the other, insuring a continuous drive at uniform speed.

To prevent over-running of the bobbins and to maintain a uniform tension on the wires or strands, I provide a grooved friction disk 30 which is engaged by the shoe 31 carried by the brake lever 32 pivoted at 33 and supported under spring tension by the spring 34, see Fig. V.

30 Stationary bobbins 35 are mounted on the hanger 5, see Fig. I. Each of these bobbins is provided with a braking means designated generally by the numeral 36 which is a substantial duplicate of the braking means described for the movable bobbins.

Referring to Fig. II it will be noted that the strand designated by the numeral 37 is led from the fixed bobbin 35 over the guide roller 38 which is in the vertical plane of the forming roller 39. Pairs of retaining rollers 40 and 41 are arranged at the sides of the guide roller 38, see Figs. I, II and III, these rollers 40, 41 being grooved so that the strands cannot slip off the guide roller.

45 From the guide roller 38 the strands pass to the rollers 42 and thence to the rollers 43, both of which are carried on the shifters 44. These shifters 44 are connected by the shifter bar 45 which is common to all of the shifters, see Fig. V, and also Fig. I where parts are broken away to disclose the shifter bar.

The rollers 42 are carried by arms 46 on the shifters so that the rollers 42 are supported at the outside of the braider heads 55 while the rollers 43 deliver the strands into the throats 18. From the braider throats the strands 37 pass to the form roller 39 to which they are guided by the holding rollers 47. The shifters 44 carry the strand 37 from one braider head to the adjacent braider head, the movement being timed so that on each rotation of the bobbin-carrier the movable bobbin strands 49 on the bobbins 28 are looped around the strands 37, see Fig. X 60 65 where the movable bobbin strands are indi-

cated in full black lines. The guide rollers 42 for the fixed bobbin strands are not mounted on shifters but are mounted on the outer frame member 3 as it will be understood that the outer strands are not shifted 70 but maintain a constant relation to the outer braider heads. To permit the strands 37 approaching close to the center of the braider heads the spacers 19 are reduced as shown at 21.

75 The braiding takes place adjacent the supporting and forming rollers 39 and 47 as indicated in Fig. IX. From the roller 39 the braided material passes to the killing rolls 50, 51 and 52, the rollers 50 and 51 being adjustably supported relative to each other and to the rolls 39 and 52 whereby the amount of stress desired is placed upon the material, this varying in accordance with the analysis of the material, that is, material high in carbon requires more "killing" than soft or low carbon materials. This killing, so-called, is to take out the tendency of the finished product to twist or distort itself, owing to the stresses resulting from the twisting and bending of the strands, having been wound on spools, drawn over rolls, and as a result of the bending operation.

80 From these killing rolls the material is passed to the take-off or capstan roller 53 95 coacting with which is the lead roller 54, the material being passed around the capstan and the lead roller 54, which has a plurality of grooves 55 therein, depending upon the number of leads required, to provide the 100 necessary draft friction to draw the material through the machine against the resistance of the various rollers and brakes described.

85 This capstan roller or wheel is carried by the shaft 56 provided with a gear 57 meshing with a pinion 58 on the shaft 59 provided with a gear 60 meshing with a pinion 61 on the driven shaft 10 so that the parts are driven in proper synchronism.

90 In the modification shown in Figs. XI and XII the forming roller 62 is substituted for the form roller 39, the roller 62 having a peripheral groove 63 therein adapted to receive the braided material at the point of braiding and the groove 63 being narrower 115 than the width of the material so that the groove folds the material upon itself longitudinally. The killing rollers 64, 65 and 66 corresponding to the rollers 52, 51 and 50 are also grooved. The result of this is that 120 the twisting tensions or stresses set up during the braiding operation, that is the twisting of the strands on the rotating bobbins, causes the material to take a spiral wind or twist as is indicated in Figs. XIII and XIV 125 producing a cable approaching circular cross section, and after passing through the killing rolls this condition is maintained, that is, there is no substantial tendency for the finished strand to further twist or coil. 130

The shifter bar 45 carrying the shifters 44 is driven from a cam 67 on the shaft 14. This cam has a cam groove 68 therein coacting with a pin 69 on the slide 70 which is connected by the link 71 to the arm 72 on the shifter bar 45, see Fig. I. This cam 67 is designed to actuate the shifters at the desired time in relation to the movement of the rotary bobbin carriers, this taking place 10 when the bobbin carriers are in the position shown in Figs. V and VI, in which position the throats 18 are unobstructed. The parts are shown in intermediate position in Fig. VI.

15 The shifters 44 are supported in the ways 73 in the frame members 2 and 3, the shifters having bearing members 74 of hard fiber or other suitable material to reduce noise and provide suitable friction reducing members.

20 By arranging the guide roller 38 in substantially the plane of the forming roller 39 the strands are under uniform tension and fed without the necessity for take-ups. This greatly simplifies the structure, reducing 25 moving parts and rendering high speed possible. Also, the elimination of high speed reciprocating parts renders high speed possible with a minimum of strain and wear on the machine.

30 I have used the term "bobbins" throughout the claims and specification as a matter of convenience in designating the strand carriers but it will be understood that it is intended to embrace therein spindles or other 35 supports for skeins, hanks and the like.

I have illustrated and described my improvements as especially designed by me for the forming of tire bead reinforcements. My improvements are, however, readily 40 adapted for general use where it is desired to form braids or fabric with uniform stresses upon the strands, or to arrange the strands so that they uniformly sustain tensile strains.

45 Having thus described my invention what I claim as new and desire to secure by Letters Patent is:

1. In a machine of the class described, the combination of a frame comprising a pair of 50 segmental frame members having facing shifter ways therein, spacers for said frame members extended to provide roller supporting spindles, gear supporting rollers mounted on said spindles, annular bobbin carrier driving gears carried by said rollers, means for driving said gears in opposite directions, 55 braider heads comprising members mounted on said frame members in opposed spaced relation providing braider throats, said head members being provided with complementary bobbin carrier ways, bobbin carriers mounted in said ways and provided with segmental gears coacting 60 with said annular gears, bobbins on said carriers, a forming roller disposed centrally relative to said braider heads, fixed bobbins, shifters 65 slidably mounted in said shifter ways and provided with guide pulleys dis-

braider heads, fixed bobbins disposed in an arc, a guide roller disposed centrally relative to said fixed bobbins and in the horizontal plane of said forming roller and over which the strands are led from said fixed bobbins, 70 shifters slidably mounted in said shifter ways and provided with pairs of guide pulleys, the inner being disposed to guide the fixed bobbin strands to said braider throats and the outer to receive the strands from 75 said guide roller, a shifter bar connecting said shifters, timed means for actuating said shifter bar, a capstan, and killing rolls interposed between said capstan and forming roller.

2. In a machine of the class described, the combination of a frame comprising a pair of segmental frame members having facing shifter ways therein, spacers for said frame members extended to provide roller supporting spindles, gear supporting rollers mounted on said spindles, annular bobbin carrier driving gears carried by said rollers, means for driving said gears in opposite directions, 85 braider heads comprising members mounted on said frame members in opposed spaced relation providing braider throats, said head members being provided with complementary bobbin carrier ways, bobbin carriers mounted in said ways and provided with segmental gears coacting 90 with said annular gears, bobbins on said carriers, a forming roller disposed centrally relative to said fixed bobbins and in the horizontal plane of said forming roller and over which the strands are led from said fixed bobbins, shifters slidably mounted in said shifter ways and provided with pairs of 95 guide pulleys, the inner being disposed to guide the fixed bobbin strands to said braider throats and the outer to receive the strands from said guide roller, a shifter bar connecting said shifters, and timed means 100 for actuating said shifter bar.

3. In a machine of the class described, the combination of a frame comprising a pair of segmental frame members having facing shifter ways therein, spacers for said frame members extended to provide roller supporting spindles, gear supporting rollers mounted on said spindles, means for driving said 115 gears in opposite directions, braider heads comprising members mounted on said frame members in opposed spaced relation providing braider throats, said head members being provided with complementary bobbin carrier ways, bobbin carriers mounted in said ways and provided with segmental gears coacting 120 with said annular gears, bobbins on said carriers, a forming roller disposed centrally relative to said braider heads, fixed bobbins, shifters 125 slidably mounted in said shifter ways and provided with guide pulleys dis-

- posed to guide the fixed bobbin strands to said braider throats, a shifter bar connecting said shifters, timed means for actuating said shifter bar, a capstan, and killing rolls interposed between said capstan and forming roller.
4. In a machine of the class described, the combination of a frame comprising a pair of segmental frame members having facing shifter ways therein, spacers for said frame members extended to provide roller supporting spindles, gear supporting rollers mounted on said spindles, annular bobbin carrier driving gears carried by said rollers, means for driving said gears in opposite directions, braider heads comprising members mounted on said frame members in opposed spaced relation providing braider throats, said head members being provided with complementary bobbin carrier ways, bobbin carriers mounted in said ways and provided with segmental gears coacting with said annular gears, bobbins on said carriers, a forming roller disposed centrally relative to said braider heads, fixed bobbins, shifters slidably mounted in said shifter ways and provided with guide pulleys disposed to guide the fixed bobbin strands to said braider throats, a shifter bar connecting said shifters, and timed means for actuating said shifter bar.
5. In a machine of the class described, the combination of oppositely driven annular bobbin carrier driving gears disposed in opposed relation, braider heads disposed in an arc and comprising members mounted in opposed spaced relation providing braider throats, said head members being provided with complementary bobbin carrier ways, bobbin carriers mounted in said ways and provided with segmental gears coacting with said annular gears, bobbins on said carriers, a forming roller disposed centrally relative to said braider heads, fixed bobbins, a guide roller disposed in the horizontal plane of said forming roller and over which the strands are led from said fixed bobbins, shifters slidably mounted in said shifter ways and provided with pairs of guide pulleys, the inner being disposed to guide the fixed bobbin strands to said braider throats and the outer to receive the strands from said guide roller, a shifter bar connecting said shifters, timed means for actuating said shifter bar, a capstan, and killing rolls interposed between said capstan and forming roller.
6. In a machine of the class described, the combination of oppositely driven annular bobbin carrier driving gears disposed in opposed relation, braider heads disposed in an arc and comprising members mounted in opposed spaced relation providing braider throats, said head members being provided with complementary bobbin carrier ways,
- 10 15 20 25 30 35 40 45 50 55 60 65
- bobbin carriers mounted in said ways and provided with segmental gears coacting with said annular gears, bobbins on said carriers, a forming roller disposed centrally relative to said braider heads, fixed bobbins, shifters slidably mounted in the horizontal plane of said forming roller and over which the strands are led from said fixed bobbins, shifters slidably mounted in said shifter ways and provided with pairs of guide pulleys, the inner being disposed to guide the fixed bobbin strands to said braider throats and the outer to receive the strands from said guide roller, a shifter bar connecting said shifters, timed means for actuating said shifter bar, a capstan, and killing rolls interposed between said capstan and forming roller.
7. In a machine of the class described, the combination of oppositely driven annular bobbin carrier driving gears disposed in opposed relation, braider heads disposed in an arc and comprising members mounted in opposed spaced relation providing braider throats, said head members being provided with complementary bobbin carrier ways, bobbin carriers mounted in said ways and provided with segmental gears coacting with said annular gears, bobbins on said carriers, a forming roller disposed centrally relative to said braider heads, fixed bobbins, shifters slidably mounted in the horizontal plane of said forming roller and over which the strands are led from said fixed bobbins, shifters slidably mounted in said shifter ways and provided with pairs of guide pulleys, the inner being disposed to guide the fixed bobbin strands to said braider throats and the outer to receive the strands from said guide roller, a shifter bar connecting said shifters, and timed means for actuating said shifter bar.
8. In a structure of the class described, the combination of oppositely driven annular bobbin carrier driving gears disposed in opposed relation, braider heads disposed in an arc and comprising members mounted in opposed spaced relation providing braider throats, said head members being provided with complementary bobbin carrier ways, bobbin carriers mounted in said ways and provided with segmental gears coacting with said annular gears, bobbins on said carriers, a forming roller disposed centrally relative to said braider heads, fixed bobbins, shifters slidably mounted in the horizontal plane of said forming roller and over which the strands are led from said fixed bobbins, shifters slidably mounted in said shifter ways and provided with pairs of guide pulleys, the inner being disposed to guide the fixed bobbin strands to said braider throats and the outer to receive the strands from said guide roller, a shifter bar connecting said shifters, and timed means for actuating said shifter bar.
9. In a structure of the class described, the combination with take-off means including a forming roller, of braider units comprising braider members disposed in spaced relation providing braider throats and having complementary bobbin carrier ways, opposed oppositely driven bobbin carrier driving gears, bobbin carriers mounted in said ways and provided with bobbins, said carriers having segmental gears coacting with
- 70 75 80 85 90 95 100 105 110 115 120 125 130

- said driving gears and adapted to engage one of said driving gears prior to disengagement with the other, fixed bobbins, shifters having guide pulleys thereon for guiding the fixed bobbin strands to said throats, operating connections for said bobbin shifters, and a guide pulley over which the strands are passed from the fixed bobbins to said shifters, said guide pulley being arranged 5 in the plane of the forming roller whereby substantially uniform tension is maintained on the strands without the aid of take-up means.
10. In a structure of the class described, the combination with take-off means including a forming roller, of braider units comprising braider members disposed in spaced relation providing braider throats and having complementary bobbin carrier ways, 15 opposed oppositely driven bobbin carrier driving gears, bobbin carriers mounted in said ways and provided with bobbins, said carriers having segmental gears coacting with said driving gears and adapted to engage 20 one of said driving gears prior to disengagement with the other, fixed bobbins, shifters having guide pulleys thereon for guiding the fixed bobbin strands to said throats, and operating connections for said bobbin 25 shifters.
11. In a structure of the class described, the combination of a forming means, braider units arranged in an arcuate relation to said forming means and comprising head members disposed in opposed spaced relation providing braider throats, said head members being provided with complementary bobbin carrier ways, oppositely driven bobbin carrier driving gears, bobbin carriers 30 disposed in said ways and provided with bobbins and with segmental gears coacting with said driving gears, reciprocating shifters adapted to shift the strands from one unit to an adjacent unit, timed driving 35 means for said shifters, fixed bobbins, and a fixed bobbin strand guiding pulley interposed between the shifters and the fixed bobbins over which the strands are passed from the bobbins to the shifters, said guide 40 pulley being disposed in substantially the plane of said forming roller.
12. In a structure of the class described, the combination of a forming means, braider units arranged in an arcuate relation to said forming means and comprising head members disposed in opposed spaced relation providing braider throats, said head members being provided with complementary 45 bobbin carrier ways, oppositely driven bobbin carrier driving gears, bobbin carriers disposed in said ways and provided with bobbins and with segmental gears coacting with said driving gears, reciprocating shifters adapted to shift the strands from one 50 unit to an adjacent unit, timed driving means for said shifters, fixed bobbins, and a fixed bobbin strand guiding pulley interposed between the shifters and the fixed bobbins over which the strands are passed from the bobbins to the shifters, said guide pulley being disposed in substantially the plane of said forming roller.
13. In a structure of the class described, the combination with take-off means, of braider units comprising braider members disposed in spaced relation providing braider throats and having complementary bobbin carrier ways, bobbin carriers mounted in said ways and provided with bobbins, driving means for said bobbins, strand shifters adapted to shift the fixed strands 55 from the throat of one unit to that of an adjacent unit, and timed actuating means for said shifters.
14. In a structure of the class described, the combination with a form roller, of braider units comprising braider head members having alined slot-like throats, bobbin carriers rotatably mounted on said head members and provided with bobbins, driving means for said bobbin carriers whereby they 60 are continuously driven in one direction, strand shifters operatively associated with said braider members for shifting the relatively fixed strands from the throat of one braider unit to that of an adjacent unit, timed actuating means for said shifters, a take-off capstan, and grooved killing rolls 65 interposed between said capstan and forming roll, all coacting for the purpose specified.
15. In a structure of the class described, the combination with a form roller, of braider units comprising braider head members having alined slot-like throats, bobbin carriers rotatably mounted on said head 70 members and provided with bobbins, driving means for said bobbin carriers whereby they are continuously driven in one direction, strand shifters operatively associated with said braider members for shifting the relatively fixed strands from the throat of one braider unit to that of an adjacent unit, 75 timed actuating means for said shifters, a take-off capstan, and killing rolls interposed between said capstan and forming roll, all coacting for the purpose specified.
16. A structure of the class described, of braider units comprising braider members disposed in spaced relation providing braider throats and having complementary bobbin 80 carrier ways, bobbin carriers mounted in said ways and provided with bobbins, driving means for said bobbins, strand shifters adapted to shift the fixed strands from the throat of one unit to that of the adjacent 85 unit, and timed actuating means for said shifters.
17. A structure of the class described, of braider units comprising head braider members having alined slot-like throats, bobbin carriers rotatably mounted on said head members and provided with bobbins, driving 90 means for said bobbin carriers whereby

they are continuously driven in one direction, strand shifters operatively associated with said head braider members for shifting the relatively fixed strands from the throat of one braider unit to that of an adjacent unit, and timed actuating means for said shifters.

18. In a structure of the class described, the combination with a take-off means, of 10 braider units comprising head members having aligned slot-like throats, bobbin carriers rotatably mounted on said head members and provided with bobbins, means for driving said bobbins continuously in one direction, 15 and a strand shifter adapted to shift a strand from the throat of one head member to that of an adjacent head member actuated in synchronism with the rotation of said bobbin carriers.

19. In a structure of the class described, the combination of braider units comprising head members with aligned throats, bobbin carriers rotatably mounted on said head members and provided with bobbins, means 25 for driving said bobbin carriers continuously in one direction, and strand shifting means for shifting a strand from the throat of one head member to that of an adjacent member synchronized with the rotation of said bobbin carriers.

20. A structure of the class described comprising braider head members having aligned slot-like throats, bobbin carriers rotatably mounted on said braider head members and 35 provided with bobbins, driving means for said bobbin carriers whereby they are continuously driven in one direction, a strand shifter operatively associated with said braider head members for shifting a strand 40 from the throat of one braider head member to that of an adjacent braider head member, and means for actuating said shifter in synchronism with said bobbin carriers.

21. A structure of the class described comprising braider head members having aligned throats, bobbin carriers rotatably mounted on said braider head members and provided with bobbins, means for driving said bobbin carriers continuously in one direction, a 45 strand shifter adapted to shift a strand from the throat of one braider head member to that of an adjacent braider head member, and means for actuating said shifter in synchronism with the rotation of said bobbin carriers.

22. In a machine of the class described, the combination of a frame comprising front and rear segmental frame members, gear supporting rollers mounted on said frame 60 members, oppositely driven annular bobbin carrier driving gears carried by said rollers, braider head members mounted on said frame members and having opposed slot-like throats, said braider head members being

provided with complementary bobbin carrier ways, bobbin carriers mounted in said ways and provided with bobbins and with segmental gears coacting with said annular driving gears, a forming roll disposed centrally relative to said fixed bobbins and head members over which the strands are led from said fixed bobbins, shifters mounted on the front frame members, said shifters being provided with guide pulleys for guiding the shifting strands from said gathering roll to 70 said throats, and means for actuating said shifters in synchronism with said bobbin carriers.

23. A structure of the class described comprising a segmental frame member having a 80 segmental shifter way therein, head members having aligned throats mounted on said frame member and provided with complementary bobbin carrier ways, bobbin carriers mounted in said ways and provided with bobbins, shifters provided with rollers coacting with said way, said shifters being provided with rollers for guiding the strands to said throats, and means for actuating said shifters synchronized with the bobbin carrier 85 driving means.

24. A structure of the class described comprising bobbins traveling in circuitous paths, means for driving said bobbins continuously in one direction in said circuitous paths, a 90 strand shifter operatively associated with said bobbins for shifting a strand alternately into the circuitous paths of said bobbins, and means for actuating said shifter in synchronism with said bobbins.

25. In a machine of the class described, the combination of a forming means, a plurality of bobbins traveling in circuitous paths, means for driving said bobbins continuously in one direction in their said circuitous paths, and a plurality of strand shifters adapted to alternately carry shifting strands into and out of the paths of adjacent bobbins.

26. In a machine of the class described, the combination with a strand forming means, of a plurality of strand supply means arranged in an arc substantially centered in said forming means and driven continuously in one direction in circuitous paths, a 110 plurality of strand shifters movable in arcuate paths centered substantially in said forming means, the paths of said strand shifters intersecting the circuitous paths of the said strand supply means whereby the 115 shifter strands are alternately brought into the paths of adjacent strand supply means, and means for guiding strands to said strand shifters disposed centrally relatively to the arcuate paths of said strand shifters.

27. In a machine of the class described, the combination with a strand forming means, of a plurality of strand supply means

arranged in an arc substantially centered in said forming means and driven continuously in one direction in circuitous paths, and a plurality of strand shifters movable in arcuate paths centered substantially in said forming means, the paths of said strand shifters intersecting the circuitous paths of the said strand supply means whereby the shifter strands are alternately brought into the 10 paths of adjacent strand supply means.

28. In a machine of the class described, the combination of a forming means and a strand gathering means arranged approximately in alignment, a plurality of strand 15 supply means delivering strands to said forming means, each of said strand supply means traveling in an independent circuitous path, means for imparting continuous circuitous movement to said strand supply 20 means, and strand shifting and guiding means whereby other strands are guided in a loop into cooperating relation with said strand supply means and strands successively brought into and out of the circuitous 25 paths of said strand supply means.

29. In braiding mechanism, forming means, strand supply means delivering strands to said forming means, said strand supply means being movable in an independent 30 closed circuit, means for imparting continuous movement to the strand supply means, strand guiding means delivering strands to said forming means and movable in a circular arc centered substantially at the forming 35 means, the paths of the strand guiding means intersecting the circuitous paths of the strand supply means, and means for shifting the strand guiding means in succe-

sion into positions within the paths of the strand supply means intersected thereby. 40

30. In braiding mechanism, forming means, strand supply means delivering strands to said forming means, said strand supply means being movable in an independent closed circuit, means for imparting continuous movement to the strand supply means, strand guiding means delivering strands to said forming means, said guiding means including means for forming a loop in the strand guided thereby, said loop being centered on a line passing through the forming means, and means for moving the strand guiding means in a circular arc centered substantially at the center of said loop, the path of one side of said loop intersecting the 55 circuitous paths of adjacent strand supply means.

31. In braiding mechanism, forming means, strand supply means delivering strands to said forming means, such strand supply 60 means being movable in substantially circular, non-intersecting paths, a strand guide member substantially aligned with the forming means, means for guiding a strand fed over said strand member in a loop before 65 it passes to the forming means, and means for shifting the loop forming means to guide one side of the loop carried thereby to intersect alternately the paths of adjacent strand supply means, said loop forming means being shifted on an arc centered substantially 70 on the line connecting the forming means and the guide member.

In witness whereof I have hereunto set my hand.

ARTHUR C. HOPKINS.
